CLAIM

The ornamental design for a surgical saw blade as shown and described.

DESCRIPTION

FIG. 1 is a top, front, and left perspective view of a surgical saw blade in accordance with my new design;

FIG. 2 is a top plan view of the surgical saw blade of FIG. 1;

FIG. 3 is a bottom plan view of the surgical saw blade of FIG. 1;

FIG. 4 is a front end elevational view of the surgical saw blade of FIG. 1;

FIG. 5 is a rear end elevational view of the surgical saw blade of FIG. 1;

FIG. 6 is a left side elevational view of the surgical saw blade of FIG. 1; and,

FIG. 7 is a right side elevational view of the surgical saw blade of FIG. 1.

The dashed broken lines in the drawings depict portions of the surgical saw blade that form no part of the claimed design.

(Continued)

The dot-dash broken lines depict the boundaries of the claim and form no part thereof.

1 Claim, 3 Drawing Sheets
